Primary Examiner — Rhea Shields*(74) Attorney, Agent, or Firm* — Perkins Coie LLP(57) **CLAIM**

The ornamental design for a combination outlet, as shown and described.

DESCRIPTION

FIG. 1 is a perspective view of an embodiment of a combination outlet.

FIG. 2 is a top plan view thereof.

FIG. 3 is a bottom plan view thereof.

FIG. 4 is a front elevation view thereof.

FIG. 5 is a back elevation view thereof.

FIG. 6 is a right side elevation view thereof; and,

FIG. 7 is a left side elevation view thereof.

In the drawings, the broken lines are for the purpose of illustrating portions of the combination outlet that forms no part of the claimed design. The combination outlet is shown with a symbolic break in its length. The appearance of any portion of the article between the break lines forms no part of the claimed design.
